UNITED STATES PATENT OFFICE.

HENRY A. BROWN, OF ABNEY, AND BEVELY B. BURKS, OF HINTON, WEST VIRGINIA.

ADDING AND SUBTRACTING MACHINE.

No. 926,166.

Specification of Letters Patent. Patented June 29, 1909.

Application filed October 8, 1908. Serial No. 456,744.

To all whom it may concern:

Be it known that we, HENRY A. BROWN, a citizen of the United States, residing at Abney, in the county of Raleigh and State of West Virginia, and BEVELY B. BURKS, a citizen of the United States, residing at Hinton, in the county of Summers and State of West Virginia, have invented certain new and useful Improvements in Adding and Subtracting Machines, of which the following is a specification, reference being had therein to the accompanying drawing.

This invention relates to computing machines and has in view certain novel and practical improvements, whereby a machine of this character may be utilized for accurately adding and subtracting any given numbers:

To this end the invention consists of a base 26 provided with an upper and a lower axis, a plurality of movable and stationary disks and rings mounted on said axes, said disks and rings being provided with graduations and numbers, means coöperating being provided between the upper and lower sets of rings and disks and indicators movable over and upon said rings and disks.

The object of the present invention is to provide a cheap and easy method of adding and subtracting any numbers from 1 to 20,000 in a rapid and accurate manner.

While the machine shown is adapted for the adding and subtracting of numbers from 1 to 20,000 it is of course understood that with slight modifications it may be made suitable for handling numbers of greater denominations.

With these and other objects in view, the invention consists of the following novel combinations and arrangements of parts hereinafter more fully described, illustrated, and claimed.

In the drawings: Figure 1 is a plan view of a computing machine embodying our invention. Fig. 2 is a longitudinal sectional view through the upper portion of the same. Fig. 3 is a similar view through the lower portion, and Fig. 4 is a detail view showing a means which may be employed to operate the indicators.

In carrying out our invention we may employ a base 1 cut away in the manner shown at 2 and 3, to provide space in which to seat the disks, but it is, of course, understood that

they may be mounted or seated in any other suitable manner.

Centrally in the upper space 2 is secured the axis 4, said axis passing through a hub 5. Secured to and extending from this hub are a plurality of radial arms 6 carrying at their outer ends a ring 7, said ring being provided with a series (preferably three) of annular rings 8 forming grooves 9 and 10. These grooves are provided with teeth 11 and 12 respectively extending entirely around their circumference, said teeth being adapted to act in conjunction with pointers 13, 14 and 15 hereinafter described. Secured between the hub 5 and a collar 16 are radial arms 17 carrying at their outer ends a ring 18 preferably of the construction shown. This last mentioned ring has its upper surface divided into a plurality of spaces or graduations containing preferably four sets of numbers, said numbers starting from zero and reading in either direction to, preferably 100. The ring 18 is secured to the axis 4 and is stationary around which the ring 7 revolves. A disk 19 is also mounted on the axis 4, and revolves within the ring 18, a coiled spring 20 being interposed between said ring 18 and the arms 17. This spring acts to hold the disk away from the collar 16 and causes it to revolve with ease and at the same time retain any position in which it may be set during the process of adding or subtracting. Annular rings 21 and 22 are carried by the disk 19 forming a groove 23, and having teeth 24 similar to the grooves 9 and 10. Indicators 25 and 26 are adapted to operate in this groove and act in conjunction with the inner row of numbers on the ring 18. The indicators 13, 14, 25 and 26 are so constructed as to be held normally in engagement with their respective rings, but upon pressing the button, carried by each indicator, they are released and free to be moved to any position around the grooves, but, upon removing the finger, are immediately locked in position.

In Fig. 4 is shown one means which may be employed for locking the indicators in position and as all of said indicators heretofore mentioned may be constructed alike, a description and detailed illustration of one will suffice for all. In the figure mentioned above a pointer 25 is shown carried by a base 27 of such shape as to move freely with-

in the groove 23, while at the same time being prevented from changing its position relative to the ring 18. This base carries a shank 28 of a button 29 and is cut away to receive said shank and one end of a slotted lever 30 pivoted therein. The opposite end of the lever 30 engages with the teeth 24 and by reference to the drawings it will be seen that by pressing upon the button 29 the indicator is released from the teeth and free to move, while releasing the button will lock the indicator. Mounted so as to revolve freely upon the axis 4 is a weighted pointer or indicator 31 having, near its outer end, 15 ears, between which is pivoted a spring pressed L-shaped lever 32 having one end projecting through said indicator and engaging teeth 33 secured to the ring 22 of the disk 19. This pointer is normally free to 20 move over the disk 19, but when the button 32^a of said pointer is pressed downward, the lever 32 engages the teeth 33 causing the disk 19 to rotate therewith.

Pivotaly mounted at 34 in the ring 18, 25 which is preferably hollow, is a segment 35 which carries two oppositely disposed pivoted arms 36 adapted to engage teeth 37 carried by the inner ring 8 of the disk 7. The segment 35 also carries an upstanding 30 pin 38 which is in the path of movement of the indicator 25 or 26, so that when either of said indicators pass the 100 mark they will swing the segment to one side and cause the arms 36 to move the ring 7 to the right 35 or left one tooth, as the case may be.

Another axis 40 is secured centrally of the cut out portion 3 of the base 1, and carries a hub 41 similar to the hub 5. Mounted upon this hub 41 by means of arms 42 is a 40 ring 43 having upon its upper surface graduations and numbers from zero to 20,000, and having, on its outer periphery, teeth 44 engaging a pinion 45 mounted in the base 1. This pinion is operated by a pin 46 carried 45 by the indicator 14, said pin striking the pinion in passing and moving the ring 43 one graduation. An inner disk 47 revolves around the axis 40 and has a groove 48 and indicators 49 and 49^a similar to those already described, while a pointer or indicator 50 similar to the pointer or indicator 31 is also mounted on said axis. It will be readily seen that by the mounting and construction of the pointers or indicators 31 and 50, that upon being released they will 50 immediately assume a position pointing to zero.

The indicator 15 which operates in the groove 9 is held and released from engagement with the ring 7 in the same manner as indicators 31 and 50, but instead of being returned to its original position by a weight, is brought back by means of a rubber or spring 15^a secured in said groove 9.

If it is desired to add the numbers 5, 10

and 25 together, by pressing the finger on the button of the indicator 25, said indicator may be brought to a position beneath the pointer 31 or opposite zero. The button of the indicator 31 is then pressed locking said 70 indicator to the disk 19, the indicator then being moved to a position pointing to 5, when it is released and allowed to assume its original position. This leaves indicator 25 pointing to the numeral 5. Then press 75 the button of the indicator 31 again and bring said indicator opposite numeral 10, thereby advancing indicator 25 to numeral 15. Release said indicator 31 once more and allow it to return to zero. Again press button of indicator 31 and move until opposite numeral 25 when indicator 25 will point to the numeral 40, that being the sum of the three numbers given. Additions may be made in this way until 100 is reached when 80 indicator 25 strikes pin of segment 35 and moves ring 7 one point to the right. At the same time a subtraction can be taking place, indicator 26 having been previously placed opposite 100 on disk 18, and if the same 85 numbers are desired to be subtracted from 100, by moving indicator 31 to numeral 5, releasing and allowing it to return to zero, then locking and moving to numeral 10 and again releasing and allowing its return. 90 Once more press the button and move to 25. These successive movements would pass indicator 26 from 100 to 95, from 95 to 85 and from 85 to 60, the difference.

Indicators 13, 14 and 15 can be operated 100 in the same manner as indicators 25, 26 and 31, 13 and 14 corresponding to 25 and 26, while 15 may be used in the same manner as 31. In this event the outer row of numerals on the ring 18 may be treated as dollars or 105 hundreds, thereby making the invention adaptable for larger amounts.

From the foregoing description it will be apparent that we have produced a cheap, simple and efficient computing machine and 110 one devoid of delicate mechanisms.

Changes in the form, proportion and minor details of construction may be made without departing from the spirit or sacrificing any of the advantages of the present 115 invention.

What we claim is:

1. A computing machine comprising a rotatable ring provided with graduations reading in opposite directions from zero to one hundred, a disk within said ring and provided with grooves having toothed edges, indicators mounted in one of said grooves and adapted to engage with one of the toothed edges and normally retained in position on opposite sides of the zero mark of the rotatable ring, and a rotatable indicator normally held at the zero mark and adapted to be engaged with one of the toothed edges of the rotatable ring.

2. A computing machine comprising a rotatable ring provided with graduations reading in opposite directions from zero to one hundred, the outer edge of said ring being 5 provided with teeth, a second rotatable ring below the first mentioned ring and also provided with a toothed outer edge, a pinion in mesh with the teeth of the lower ring, a disk mounted within each of said rings and provided 10 with grooves having toothed edges, indicators mounted in each groove and adapted to engage with the toothed edges thereof, a rotatable indicator for each disk and also adapted to have a detachable engagement 15 with the teeth in one of said grooves, and a second set of indicators carried by the upper rotatable ring one of which is adapted to contact with said pinion to impart a movement to the lower rotatable ring.
- 20 3. A computing machine comprising two rotatable rings held in spaced relation, one of said rings being provided with a toothed outer edge, a pinion in mesh with said toothed edge, a disk within each ring and 25 provided with grooves having toothed edges, adding and subtracting indicators mounted in the grooves of each disk and adapted to engage with the toothed edges thereof, an indicator rotatable over each disk and adapted 30 to engage with the teeth of one of the edges thereof, and indicators carried by one of the rings, one of said indicators being adapted to contact with said pinion to cause it to impart a movement to the ring with 35 which it is in mesh.
4. A computing machine comprising a base, rotatable rings mounted thereon, disks within said rings, said disks being provided with grooves having toothed edges, indicators movable over said disks, and a spring 40 pressed lever carried by said disks and adapted to engage with the toothed edges of the grooves to hold said indicators in engagement therewith.
- 45 5. A computing machine comprising a base, rotatable rings mounted thereon, disks within said rings, said disks being provided with grooves having toothed edges, indicators movable over said disks, and a locking
- lever carried by each indicator and adapted 50 to hold the same in engagement with the toothed edges of said grooves.
6. A computing machine comprising a base, rotatable rings mounted thereon, a disk within each ring and provided with an annular grooves having toothed edges, indicators movable over said disks, a locking lever carried by each indicator and having a button whereby the same may be placed in engagement with the toothed edges of the 55 grooves and a spring for normally holding said levers out of engagement with said edges.
7. A computing machine comprising a base having openings therein, a ring rotatably mounted in each opening, one of said rings being provided with a toothed outer edge, a pinion in mesh with said toothed edge, a grooved disk within each of said rings, and having teeth formed in each 60 groove, indicators movable over said disks and adapted to have a locking engagement with the toothed edges of the grooves, and a projection carried by one of said indicators and adapted to contact with the said 65 pinion to impart a movement to the rings with which it is in mesh.
8. A computing machine comprising a rotatable ring and a disk, indicators movable over said disk and coöperating with the rotatable ring for adding or subtracting numerals between zero and one hundred, a second rotatable ring adjacent to the first mentioned ring, a disk within the second ring, indicators movable over the last mentioned disk and coöperating with its surrounding ring to add or subtract numbers of higher denomination than the first mentioned ring, and means carried by the first mentioned ring for imparting a movement 80 to the second mentioned ring.

In testimony whereof we hereunto affix our signatures in presence of two witnesses.
